CODED TRACK CIRCUIT SIGNALING SYSTEM
FOR RAILROADSThomas J. Judge, Rochester, N. Y., assignor to
General Railway Signal Company, Rochester,
N. Y.

Application May 22, 1947, Serial No. 749,742

11 Claims. (Cl. 246—34)

1

This invention relates to coded track circuit signaling systems for railroads, and it more particularly pertains to the conservation of energy in coded track circuits.

It is well known that a higher degree of track circuit energization is required to obtain satisfactory operation of a code following track relay at a fast code rate than at a slow code rate, assuming the same percentage of "on" and "off" time for each code rate. This is true because of the inductive windings of the track relays requiring time for current to build up, and for a short pulse which does not allow time for full build up of the current it is necessary to use a higher energizing potential in order that the current may build up for each pulse to the operating value of the relay. Thus it is the usual practice to adjust the potential applied to the track circuit to obtain satisfactory operation at the highest code rate employed. Such arrangement obviously provides a higher drain on the source of track circuit energy than is required for the lower code rate, and thus track circuit power, which is often necessarily furnished by primary batteries, is wasted.

An object of the present invention is to reduce the power consumption in a coded track circuit, and yet maintain the same degree of dependable operation, by applying a lower potential to the track rails for the transmission of pulses at a lower code rate than is applied for the transmission of pulses at a higher code rate.

Another object of the present invention is to increase the resistance in series with the source of energy connected to the track rails in response to the presence of a train in the associated track section.

Another object of the present invention is to reduce the code rate in a track section in response to the presence of a train in that track section and thereby insert a higher resistance in series with the track rails and the source of energy for the track circuit.

Another object of the present invention is to reduce the power consumption of code receiving apparatus by rendering some of such apparatus energized only in response to approach control.

Other objects, purposes, and character features of the present invention will be in part obvious from the accompanying drawings, and in part pointed out as the description progresses.

In describing the invention in detail, reference is made to the accompanying drawings in which like letter reference characters are generally used to designate similar parts which are made dis-

2

tinctive by reason of preceding numerals characteristic of the particular location or signal with which such parts are associated, and in which:

Fig. 1 illustrates one embodiment of the present invention as applied to specific typical track sections of a stretch of railway track; and,

Fig. 2 illustrates another embodiment of the present invention as applied to certain typical track sections of a stretch of railway track.

10 For the purpose of more clearly illustrating the mode of operation of the system provided by the present invention, rather than illustrating the specific structure and arrangement of parts that would be employed in practice, the respective embodiments of Figs. 1 and 2 of the drawings have been illustrated by schematic wiring diagrams of a conventional nature. The symbols (+) and (—) in the diagrams are used to indicate connection to the respective positive and 20 negative terminals of a suitable direct current source of energy.

With reference to Fig. 1, a stretch of railway track is illustrated as being divided into respective track sections 1T, 2T, 3T and 4T in a manner commonly employed in railway signaling practice, and the signals 2, 3, and 4 are provided for governing entrance to the respective track sections 2T, 3T, and 4T for governing east-bound traffic (to the right).

30 The signals illustrated are of the color light type having respective green, yellow, and red color lamp units for indicating proceed, proceed with caution, and danger respectively. It is to be understood, and it will be readily apparent as 35 the description progresses, that the present invention is applicable to systems employing other conventional types of signals such, for example, as searchlight, position light, or semaphore signals.

40 The track circuit code transmitting apparatus associated with the exit end of each of the track sections of Fig. 1 comprises a source of energy which must in some cases necessarily be a primary battery, code transmitter oscillators 15CT and 45 180CT for generating respective 75 and 180 code rates, and approach control relays AR, ARS and ARP. The code oscillators can be of any dependable type for generating code pulses at respective 180 and 75 code rates, each pulse being of a length substantially equal to the time spaces between pulses. A suitable oscillator of this character is disclosed in the patent to O. C. Field Patent No. 2,351,588, dated June 20, 1944.

The code receiving apparatus at the entrance 55 end of the respective track sections comprises a

track relay TR connected across the track rails, and conventional code responsive relays H and D which are of a character to be maintained steadily picked up in response to the pulsing of the associated track relays TR. The relays D respond only to the pulsing of their associated track relays TR at a 180 code rate and when approach control has become effective.

The signaling system according to Fig. 1 is assumed to be such that the signals are normally conditioned to be clear (subject to approach control) when the trackway is unoccupied by trains. Under such conditions, the code transmitter oscillators 180CT for the respective track sections are normally active to apply code pulses to the track rails at the respective exit ends of the track sections at a 180 rate and the oscillators 75CT are inactive. For example, the oscillator 180CT associated with the exit end of the track section 2T is normally active in accordance with the energization of a circuit extending from (+) including front contact 20 of relay 3H, back contact 21 of relay 2ARP, and winding of relay 180CT, to (-).

In accordance with the code oscillator 180CT being normally active, code pulses at a 180 rate are applied across the track rails at the exit end of each of the track sections as is specifically shown, for example, for the application of code pulses to the track rails at the right hand end of the track section 2T. The relay 2TR at the left hand end of the track section 2T is energized for each pulse of the oscillator 180CT by a circuit extending from the positive terminal of the battery 22 including the variable resistor R1, front contact 23 of oscillator 180CT, back contact 24 of relay 2ARP, front contact 25 of relay 3H, upper rail of track section 2T, winding of relay 2TR, track resistor R2 and lower rail of track section 2T, to the negative terminal of the battery 22. A consideration of the circuit which has been described shows that the voltage applied across the track rails by the code transmitter is limited by the variable resistor R1, which resistor is adjusted in practice to provide the required amount of operating current for the track relay 2TR at the 180 rate.

It is well known in coded track circuit organizations that difficulties are encountered at times in coded track circuit operation because of a potential set up in the ballast between the track rails which is not immediately dissipated upon the termination of each code pulse. It is therefore desirable according to the present invention, although not necessarily required for the operation of some features of the present invention, that a shunt be applied across the track rails by the track circuit code transmitter during the off period between code pulses to accelerate the dissipation of a potential build up between the rails by the track ballast. It is therefore provided, subsequent to the opening of the track circuit at front contact 23 at the termination of each of the code pulses generated by the code transmitter relay 180CT, that a shunt is closed across the track rails upon the closure of back contact 26 of the oscillator 180CT during each off period of the code being transmitted. Such shunt in the track section 2T can be traced as extending from the upper rail of the track section 2T including front contact 25 of relay 3H, back contact 24 of relay 2ARP, and back contact 26 of oscillator 180CT to the lower rail of the track section 2T. Such shunt is obviously removed when the oscillator 180CT shifts its contacts to close its

front contact 23 for initiating the application of another code pulse across the track rails. The use of the shunt as has been described during the off periods of the code provides for satisfactory operation of the track relay 2TR at a minimum voltage applied across the track rails by the code transmitter 180CT at the right hand end of the track section 2T.

The track relays TR are preferably of the biased polar type adapted to pulse their contacts in response to code pulses received through the track rails, and when the track rails of the associated track sections are shunted as by the presence of trains, the back contacts of the relays TR are steadily closed.

The pulsing of the contact 27 of relay 2TR in accordance with the 180 code received at the left hand end of the track section 2T provides for the clearing of signal 2 as indicated by the dotted line 28 in a manner corresponding to that which is specifically illustrated for the clearing of signal 3 in accordance with the pulsing of the track relay 3TR.

The pulsing of contacts 29 and 30 of relay 3TR is effective to energize the direct current relay 3H through the decoding transformer 31 and the rectifying contact 30 in a manner well known to those skilled in the art. With the relay 3H picked up, the closure of front contact 32 conditions a circuit for the relay 3D by which such relay can be energized when approach control for the signal 3 is rendered effective. The closure of front contact 33 of relay 3H in the control circuit for the lamps of signal 3 conditions a circuit for the energizing of the green or yellow lamp of such signal, as selected by the relay 3D, but the lamps are normally dark because of the front contact 34 of relay 2ARP being open.

Having thus considered the conditions of the system which can be assumed to be the normal conditions, when the trackway is unoccupied by trains, consideration will now be given to the mode of operation of the signaling system under certain typical traffic conditions.

It will thus be assumed that an eastbound train accepts the signal 2 and enters the track section 2T. The presence of the train in track section 2T, by shunting the track rails of that track section, causes increased current flow through the series resistor R1 which is included in the track circuit which has been described, and the increased voltage drop across this resistor is effective to cause the relay 2AR to become active. The relay 2AR is connected in multiple with the resistor R1 by a circuit extending from the right hand terminal of the resistor R1 and including resistor R4 and back contact 35 of relay 2ARP, front contact 36 of relay 3H and winding of relay 2AR to the left hand terminal of the resistor R1.

The structure of the relay 2AR is preferably of the general character of the code following track relays TR so as to follow the code as applied to the track rails of the track section 2T when that track section is shunted. The pulsing of the contact 37 of relay 2AR causes the relays 2ARS and 2ARP to become successfully picked up. When the relay 2ARS is picked up by the pulsing of contact 37 of relay 2AR, it is maintained steadily energized by its stick circuit for a time interval required to effect the picking up of relay 2ARP, which is preferably made to have slow pick up characteristics. Such stick circuit extends from (+), including back contact 34 of relay

2ARP, front contact 38 of relay 2ARS, and winding of relay 2ARS, to (—). The relay 2ARS has sufficiently slow drop away characteristics as to be maintained steadily picked up in response to the pulsing of the contact 37 of relay 2AR in its pick up circuit after its stick circuit is opened by the picking up of relay 2ARP.

Immediately upon the picking up of the relay 2ARS, a circuit is closed connecting the transformer 39 to the coding contact 29 of relay 3TR, and thus rendering the energization of the relay 3D effective in accordance with the 180 code rate being received at the left hand end of the track section 3T. More specifically, a circuit is closed for the upper portion for the primary winding of the decoding transformer upon the closure of front contact 29 of relay 3TR. Such circuit extends from (+) including front contact 29 of relay 3TR, front contact 48 of relay 2ARS, and upper portion of the primary winding of transformer 39, to (—). The dropping of the relay 3TR at the end of each pulse opens the circuit which has been described at front contact 29 and closes a circuit at back contact 29 for the lower portion of the primary winding of the transformer 39. Such circuit extends from (+) including back contact 29 of relay 3TR, front contact 32 of relay 3H, front contact 41 to relay 2ARS, and lower portion of the primary winding of the transformer 39, to (—).

The output of the decoding transformer 39 is coupled to the input terminals of the tuned circuit and rectifier unit 180DU, such unit being of the character generally employed for similar purposes in coded track circuits. The direct current relay 3D is connected to the output terminals of the tuned circuit and rectifier unit 180DU so as to render that relay picked up only in response to a 180 code received at the left hand end of the track section 3T. It has already been pointed out that the relay 3D is normally de-energized, even though there may be a 180 code in the track section 3T, because of such relay approach controlled by the relay 2ARS. Thus, relay 3D, and the decoding transformer 39 as well, receives energy only when the track section 2T is occupied by a train which has advanced sufficiently in approach of the signal 3 as to render the approach relay 2AR active.

It will be seen by the sequence of operation of the relays 2ARS and 2ARP, together with the slow pick-up characteristics of 2ARP, that sufficient time is allowed for the picking up of relay 3D in response to the picking up of relay 2ARS before the signal circuit is closed by front contact 34 of relay 2ARP. This prevents a possible flash of the yellow lamp Y of signal 3 if the relay 2ARP were to become picked up prior to the picking up of the relay 3D. The use of the stick circuit for the relay 2ARS to maintain that relay steadily picked up immediately subsequent to its initial energization provides in a positive manner that the continuity of the circuit for the primary winding of the transformer 39 is maintained to insure a quick response of the relay 3D.

The closure of front contact 42 of relay 2ARS upon the picking up of that relay applies energy to the winding of relay 2ARP in an obvious manner, and upon the pick up of relay 2ARP, the opening of back contact 34 opens the stick circuit for relay 2ARS, as the function of such stick circuit in a manner which has been heretofore described is completed at that time.

Upon the picking up of the relay 2ARP, with the relays 3H and 3D already picked up, the

green lamp G of signal 3 becomes energized by a circuit extending from (+) including front contact 34 of relay 2ARP, front contact 33 of relay 3H, front contact 43 of relay 3D and the lamp G, to (—). It is thus provided that the approaching control of the signal 3 is effective upon the approach of a train within the track section 2T to apply energy to the signal and thus provide a signal indication governing passage of the train into the next block.

The picking up of relay 2ARP also has another function in that it shifts the code rate applied to the track rails of the track section 2T from a 180 rate to a 75 rate, and in doing so reduces the power drain on the track battery 22 because of the resistor R3 associated with the 75 code rate transmission being of a higher value than the resistor R1 associated with the 180 code rate transmission. It is also provided that the code transmitter 180CT is rendered inactive upon the picking up of relay 2ARP by the opening of back contact 21, and the code transmitter 75CT is rendered active in accordance with the closing of a circuit extending from (+), including front contact 20 of relay 3H, front contact 21 of relay 2ARP, and winding of oscillator 75CT, to (—).

The picking up of relay 2ARP is effective to open the branch of the track circuit including the 180 code oscillator contacts 23 and 26 at back contact 24, and the closure of front contact 24 of relay 2ARP renders the transmission of code pulses effective at a 75 rate. Thus a reduced potential is applied across the track rails at the right hand end of the track section 2T. The circuit by which such pulses are applied extends from the positive terminal of the track battery 22 including the adjustable resistor R3, front contact 44 of the oscillator 75CT, front contact 24 of the approach control relay 2ARP, front contact 25 of relay 3H, upper rail of track section 2T, winding of relay 2TR, track resistor R2, and lower rail of track section 2T, to the negative terminal of the track battery 22. It is thus provided that the power consumed in the track circuit for the track section 2T is reduced because of the presence of the train in the track section upon the shifting of the code rate from a 180 to a 75 rate because of the selective inclusion of a higher resistance for the 75 code rate than for the 180 code rate.

During the off periods of the code, the closure of back contact 45 of oscillator 75CT shunts the track rails as has been described with respect to the shunting of the track rails by back contact of oscillator 180CT.

Inasmuch as the approach control relay 2AR is energized principally by the voltage drop across the track resistor, the control circuit of such relay must be selectively controlled so as to shift the control of that relay from one track resistor to the other as the code rate in the track section is changed. Thus it is provided that the picking up of the relay 2ARP as has been heretofore described not only shifts the code rate applied to the track section 2T, but also shifts the connection of the approach control relay 2AR so that such relay, rather than being energized by the voltage drop across the resistor R1, is energized by the voltage drop across the resistor R3. This shifting of the control circuit for the relay 2AR is accomplished upon the shifting of contact 35 to select between the resistor R1 and R3 in an obvious manner, the resistor R5 being included in the circuit rather than the resistor R4 of relatively lower resistance. This maintains substan-

initially the same voltage across relay 2AR upon shifting from the voltage drop across R1 to the voltage drop across R3.

Upon the shifting of the code rate from a 180 code to a 75 code, the current in the track circuit is reduced in a manner which has been heretofore described, and thus the current is less through the resistor R3 than formerly existed through the resistor R1. The resistance R3 being greater than R1 provides that the potential drop across the resistor R3 for the operation of the approach control relay 2AR is of a value relatively close to the potential drop across resistor R1 by which the relay 2AR is assumed to have been initially rendered active. Because of the reduction of current in the remainder of the track circuit, the potential drop across such remainder of the circuit decreases, and thus the drop across R3 must be greater to some extent than the prior drop across R1. This is desirable because it provides that once the approach relay 2AR has been rendered active, it is maintained active at a higher potential rather than being operated at a marginal potential, and thus is more positive in its operation.

Assuming the train to progress farther along the trackway so as to accept the signal 3 and enter the track section 3T, the shunting of the track rails of the track section 3T causes the relay 3H to be dropped away, and the dropping away of that relay, upon the closure of back contact 33, with the relay 2ARP still in its picked up position, provides for the energization of the red lamp R of signal 3. The green lamp G of that signal is deenergized upon the shifting of that contact.

In accordance with the dropping away of relay 3H, the code oscillator 75CT is maintained active, and the oscillator 180CT is maintained inactive in an obvious manner by the shifting of contact 20.

In the track circuit for the track section 2T, the track rails are maintained energized with code pulses at a 75 rate by a circuit extending from the positive terminal of the track battery 22 including the variable resistor R3, front contact 44 of oscillator 75CT, back contact 25 of relay 3H, upper rail of track section 2T, winding of the track relay 2TR, variable resistor R2, and lower rail of track section 2T, to (-). During the off periods of the code, the track rails are shunted from the upper rail through back contact 25 of relay 3H and back contact 45 of oscillator 75CT, to the lower rail of the track section 2T. The closure of back contact 36 of relay 3H maintains the relay 2AR active as long as the train shunt is maintained in the track section 2T.

It will be readily apparent that the code transmitter at the right hand end of the track section 2T is effective to apply 75 code pulses to the track rails as long as the relay 3H remains in its dropped away position, irrespective of the approach relay 2AR being rendered inactive when the track section 2T becomes unoccupied in the rear of the train. The rendering inactive of relay 2AR under such conditions causes the relay 2ARS to be dropped away when the contact 37 of relay 2AR is rendered inactive, and thus the opening of front contacts 40 and 41 of relay 2ARS is effective to disconnect the relay 3D and its decoding transmitter from the track contact 29 of relay 3TR. The opening of front contact 42 of relay 2ARS provides for the dropping away of relay 2ARP, and upon the dropping away of that relay, the opening of front contact 34 ex-

tinguishes the red lamp R of signal 3 and thus restores that signal to its normally dark condition.

Upon further progress of the eastbound train so as to leave the track section 3T unoccupied in the rear of the train, a 75 code transmitted through the track rails of the track section 3T is effective to cause the picking up of relay 3H to complete the restoration of the track circuit apparatus for the track section 2T to the conditions which have been described when considering the normal conditions of the coded track circuits when no trains are present. The picking up of relay 3H under such conditions changes the code rate in track section 2T from a 75 code to a 180 code by the shifting of contacts 20 and 25, and contact 36 shifts the connection to the relay 2AR from resistor R3 to resistor R1, which resistor is associated with the transmission of code pulses at a 180 rate.

With reference to Fig. 2 another embodiment of the present invention is illustrated in which the approach control and reduction in code rate upon the approach of a train is accomplished by the use of inverse code rather than by the use of series or shunt type approach control relays.

The trackway to which the signaling system is applied comprises respective track sections 11T, 12T, 13T and 14T, and signals 12, 13, and 14 are provided for governing entrance into respective track sections 12T, 13T, and 14T. Signaling is provided for governing the movement of eastbound train (to the right), and the signals can be of any conventional signal structure as has been heretofore pointed out. Code transmitter oscillators 75CT and 180CT correspond to oscillators which have been described specifically with reference to Fig. 1, and inasmuch as an inverse code receiver track relay is required at the exit end of each of the track sections, the track relays associated with each track section are designated as relays ATR and BTR provided with suitable prefixes. A relay ATR is at the entrance end of the track section for receiving driven code pulses, and a relay BTR is at the exit end for receiving inverse code pulses. The relays ATR are of the conventional code following biased polar type, while the relays BTR are illustrated as being of the magnetic stick type, particularly for the purpose of improving the operating characteristics of the track circuit with respect to the reception of inverse codes. It is to be understood, however, that other types of code following relays can as well be used in accordance with the requirements of practice.

To consider first the condition of the apparatus when no trains are present, conveniently calling the normal condition of the system, it will be assumed that there are no trains present in the trackway, and the condition of the relays at that time is as illustrated in Fig. 2 in which it is shown that the oscillator 180CT is normally active for the transmission of a 180 code in the track section 12T and the oscillator 75CT is normally inactive. The track circuit for each code pulse of the oscillator 180CT is closed from the positive terminal of the track battery 50 including the variable resistor R10, contact 51 of oscillator 180CT in its upper position, back contact 52 of relay 12AP, front contact 53 of relay 13H, upper rail of track section 12T, winding of relay 12ATR, back contact 54 of the inverse code transmitter relay 12RCP, variable resistor R20, lower rail of track section 12T, and lower winding of the inverse code receiver relay 12BTR, to the negative terminal of

the track battery 50. The lower winding of the inverse code receiver relay 12BTR is so connected as to actuate the contacts of the relay 12BTR to their lower positions.

In response to the pulsing of contact 55 of the driven code receiver relay 12ATR, the relay 12H (not shown) is picked up in a manner corresponding to that specifically illustrated for the energization of the relay 13H which is associated with the control of the signal 13. The relay 13H is illustrated as being energized normally through the pulsing of contacts 56 and 57 of the code following track relay 13ATR.

At the termination of each driven code pulse transmitted from the right-hand end of the track section 12T, the relay 12RCP is picked up for the transmission of an inverse code pulse in a manner corresponding to that which is specifically illustrated for the pick up of the relay 13RCP at the entrance end of the track section 13T. Thus the relay 13RCP is illustrated as being picked up upon the termination of a driven code pulse when a circuit is closed extending from (+), including back contact 56 of the code following track relay 13ATR, front contact 58 of relay 13H, rectifier 59, back contact 60 of relay 13RCT, and winding of relay 13RCP, to (-). At the same time energy is applied to the winding of the relay 13RCT except that it is applied through the variable reactor 61, and thus the picking up of the relay 13RCT is delayed to provide timing for measuring the duration of the inverse code pulse being transmitted. It will be readily apparent that the adjustment of the variable reactor 61 can readily be effective to govern the pick up time of the relay 13RCT. The pick up circuit for the relay 13RCT extends from (+), including back contact 56 of relay 13ATR, front contact 58 of relay 13H, rectifier 62, variable reactor 61, and the winding of relay 13RCT, to (-). When the relay 13RCT is picked up, the opening of back contact 60 deenergizes the inverse code transmitter relay 13RCP, and causes that relay to be dropped away. Such relay in dropping away connects the track relay 13ATR across the track rails through back contact 63 and the variable track resistor R50 to condition relay 13ATR for the reception of the next driven code pulse transmitted from the right-hand end of the track section 13T. The connection of the track relay 13ATR across the track rails at the entrance end of the track section 13T under such conditions allows such relay to respond to the next driven code pulse, and in its picking up, the opening of back contact 56 opens the circuits which have been described for the energization of relays 13RCT and 13RCP for the duration of the reception of the driven code pulse. The rectifiers 59 and 62 in the circuits for relays 13RCP and 13RCT are to effectively isolate the relays 13RCP and 13RCT from the primary winding of the transformer 64. The resistor 65 provides a desired slow drop away characteristic for relay 13RCT by shunting its winding and the reactor 61.

Having thus considered the manner in which the respective inverse code transmitter relays are active, consideration will now be given to the transmission of the inverse code pulses through the track rails, and the reception of such pulses at the exit end of a typical track section. Thus, with reference to the track section 12T, the picking up of the relay 12RCP for the transmission of an inverse code pulse is effective to open the track circuit which has been described at back contact 54 and apply the potential of the track

battery 66 across the track rails at the entrance end to track section 12T through the variable resistor R60 and front contacts 67 and 54 of relays 12RCP.

The application of such energy to the track rails is effective to energize the magnetic stick relay 12BTR with a polarity to cause such relay to actuate its contacts to their upper positions. The circuit by which the relay 12BTR is energized in response to an inverse code pulse extends from the positive terminal of the track battery 66 including the variable resistor R60, front contact 67 of relay 12RCP, front contact 54 of relay 12RCP, upper rail of track section 12T, front contact 53 of relay 13H, back contact 52 of relay 12AP, contact 68 of oscillator 180CT in its lower position, upper winding of relay 12BTR, and lower rail of track section 12T to the negative terminal of the track battery 66. The termination of the inverse code pulse by the dropping away of relay 12RCP reestablishes the connection for the driven code receiver track relay 12ATR across the track rails at the left hand end of the track section 12T.

The pulsing of contact 69 of the inverse code receiver relay 12BTR in response to the inverse code is effective through the decoding transformer 70 and the rectifier contact 71 to maintain the relay 12BH steadily energized, relay 12BH having slow drop away characteristics so as to be maintained steadily picked up in response to the pulsing of the code receiver relay 12BTR.

With relay 12BH picked up, connections to the decoding transformer 64 associated with the control of the relay 13D are opened at back contacts 72 and 73 so as to cause that transformer and the relay 13D to be normally deenergized. The relay 12AP is normally deenergized because the dropping away of relay 12BH is required for closing its pick up circuit. It is thus provided that energy consumption aside from that required for the track circuits at a signal location is limited to that required for the operation of the oscillator 180CT, for the energization of the relays H and BH at that signal location, and for the actuation of the inverse code transmitter relays RCT and RCP.

To consider the mode of operation of the system according to the embodiment illustrated in Fig. 2 upon the passage of a train, it will be assumed that an eastbound train enters the track section 12T upon accepting the signal 12. The shunting of the track rails of the track section 12T renders the transmission of an inverse code ineffective in that track section for the operation of the relay 12BTR. When the contacts 69 and 71 of relay 12BTR become inactive because of the train shunt, the relay 12BH becomes dropped away, and the dropping away of that relay, upon the closure of back contacts 72 and 73, connects the decoding transformer 64 to the contact 56 of the track relay 13ATR so as to provide for the energization of the relay 13D through the rectifier and tuned circuit unit 180DU.

The dropping away of relay 12BH is also effective upon the closure of back contact 74 to energize the relay 12AP, which preferably has slow pick up characteristics so as to allow time for the picking up of the relay 13D prior to the closure of front contact 75 of relay 12AP in the signal control circuit.

Upon the closing of front contact 75 of relay 12AP, with the relays 13H and 13D picked up, the green lamp G of signal 13 is energized by

a circuit including front contact 75 of relay 12AP, front contact 76 of relay 13H, and front contact 77 of relay 13D. The approach of the eastbound train within the track section 12T has thus become effective to energize the green lamp G of signal 13 for governing passage of the train into the track section 13T.

Upon the picking up of relay 12AP, the oscillator 180CT (associated with the code transmitter at the exit end of track section 12T) is rendered inactive, and the oscillator 75CT is rendered active by the shifting of contact 78 of relay 12AP.

When the oscillator 180CT becomes inactive, its contacts 51 and 68 assume their center positions which have been shown dotted in Fig. 2, thus opening all circuits selected by such contacts. The contacts 79 and 80 of the oscillator 75CT by becoming active alternately close their front and back contacts to transmit a 75 code through the track rails of the track section 12T. The relay 12BTR has its upper winding connected across the track rails by the back contact 80, but the train shunt of track section 12T renders that relay inactive.

The positive terminal 50 of the track battery is connected to the upper rail of the track section 12T for each 75 code pulse in a circuit including the variable resistor R30, contact 79 of oscillator 75CT in its upper position, front contact 52 of relay 12AP, and front contact 53 of relay 13H to the upper rail of track section 12T. The negative terminal of the track battery is connected to the lower rail of the track section 12T for each pulse of the 75 code through the lower winding of the inverse code receiving relay 12BTR. It has been pointed out that energy flowing through the lower winding of the relay 12BTR is of a polarity to actuate the contacts of that relay to their lower positions, and that the actuation of such contacts to their upper positions can be comprised only by the reception of inverse code pulses as applied to the upper winding of the relay 12BTR. It is thus provided that the energy consumption of the track section 12T has been reduced in response to the presence of the train by the shifting of the driven code rate in that track section from a 180 to a 75 code, and thus selecting the inclusion of the higher value resistor R30 in series with the track battery 50 as compared to the value of the resistance R20 that is normally included in series with the track battery 50 for the transmission of a 180 code.

As the train progresses so as to accept the signal 13 and enters the track section 13T, the shunting of the track rails of that track section renders the track relay 13ATR inactive and thus causes the dropping away of the relays 13H and 13D. The shifting of contact 76 of the relay 13H is effective to open a circuit for the green lamp G of signal 13 and close an obvious circuit for the red lamp R of such signal. It is of course desirable that the relay 13H drop away prior to the dropping away of relay 13D to avoid a flash of the yellow lamp Y of signal 13.

Upon the dropping away of relay 13H, the circuit by which the oscillator 75CT has been active is opened at front contact 81, but the closure of back contact 81 maintains such oscillator active. Similarly in the track circuit, the shifting of contact 53 of relay 13H opens the circuit that has been described for the transmission of 75 code pulses and closes a circuit to maintain the transmission of 75 code pulses which shunts front contact 52 of the approach

control relay 12AP out of the circuit which has been described. The reception of the 75 code pulses at the left hand end of the track section 12T when such track section has become unoccupied in the rear of the train renders the code following track relay 12ATR active at the 75 code rate to pick up its associated relay 12H (not shown) and thus provides for the energization of the yellow lamp Y of signal 12 in case a following train is approaching so as to provide approach control for the illumination of that lamp. The inverse code transmitter relay 12RCP is rendered active in accordance with the pulsing of the track relay 12ATR by the energization of circuits similar to those which have been described with reference to the control of the inverse code transmitter relay 13RCP.

As the train progresses further along the trackway so as to leave the track section 13T unoccupied, the establishment of a 75 code in that track section is effective to restore the relay 13H to its normally energized position, and in accordance with the picking up of that relay the shifting of contacts 81 and 53 is effective to restore the conditions which have been described as normal whereby the oscillator 75CT is rendered inactive, and the oscillator 180CT active for the transmission of a 180 track circuit code in the track section 12T. Such restoration is of course effective only provided no following train has entered the track section 12T. In case a following train has entered the track section 12T, it will be readily understood by those skilled in the art that the mode of operation of the system becomes effective upon the approach of such following train in a manner corresponding to that which has been described when considering specifically the passage of a single train.

To summarize various respective features of the present invention that are effective to save energy, with reference to Fig. 1, it has been described that the shifting of the code rate from a 180 to a 75 rate upon the entrance of a train into the associated track section is effective to reduce the potential across the track rails by the selection of a higher track circuit resistance in series with the track battery. It is also provided according to Fig. 1 that the approach control relay 2AR can be made a relay of relatively high efficiency because such relay is arranged to operate off the voltage drop across the track resistor R1 or R3 included in series with the battery, and thus the windings of such relay can be of high resistance with a large number of turns, as compared to the low resistance winding that would be required if such approach control relay were to be actuated solely because of its inclusion directly in series with the track battery and the track rails.

Further energy saving features of the embodiment according to Fig. 1 are that the oscillators 75CT and 180CT are selectively rendered active in accordance with whichever oscillator is required to be active. The circuits including the decoding transformer 39 and its associated tuned circuit 180DU and relay 3D are normally de-energized, and their energization is rendered effective only in response to approach control.

Considering the energy saving features according to Fig. 2, it will be apparent that energy is saved in each track circuit when such track circuit is occupied by a train by the shifting of the code rate from a 180 to a 75 code and thus including a higher value track resistor in series with the track battery. The inverse code re-

ceiver relay 12BTR that is normally active of course consumes a certain amount of power, as does any approach control device that must necessarily be associated with a track circuit. The oscillators 75CT and 180CT of Fig. 2 are selectively rendered active as in Fig. 1, and similarly there is no energy consumed by the relay D and its associated decoding transformer except when approach control is rendered effective. The inverse code transmitter relays RCT and RCP are normally active, but their power consumption can be maintained at a very low level as compared to the power saved by the use of a higher resistance in series with the respective track circuits when their associated track sections are occupied by trains.

Having thus described two specific embodiments of the present invention as limited to specific stretches of railway track, it is desired to be understood that these forms have been selected more for the purpose of facilitating the typical disclosures of the present invention than for limiting the scope of the present invention, and it is to be further understood that various additions, alterations and modifications may be applied to the specific form shown to meet the requirements of practice, without in any manner departing from the spirit or scope of the present invention except as limited by the pending claims.

What I claim is:

1. In a code transmitter for applying code pulses at selected high and low code rates to the track rails of a track section, a source of energy, circuit means including said source of energy for applying code pulses at a relatively high potential to the track rails at said high code rate, circuit means including said source of energy for applying code pulses at a relatively low potential to the track rails at said low code rate, and circuit means dependent upon traffic conditions for selecting the application of high or low code rate pulses to the track rails.

2. In a railway track circuit code transmitter for applying code pulses across the track rails of a track section at selected high or low code rates, a source of energy, respective high and low rate coding contacts, respective high and low resistance track resistors, circuit means for selectively connecting said source of energy across the track rails through said high rate contact and said low rate contact and said relatively high resistance track resistor, whereby a higher potential is applied to the track rails at said high rate than at said low rate.

3. In a coded track circuit for a railway track section, a track circuit code transmitter at one end of the track section comprising a source of energy, respective high and low rate code oscillators, and circuit means for selectively connecting said source of energy across the track rails of said track section through a contact of said high rate oscillator or a contact of said low rate oscillator, said means being effective to apply a higher potential to the track rails through said contact of said high rate oscillator than through said contact of said low rate oscillator.

4. In a coded track circuit of the character described for a railway track section, a code transmitter at one end of the track section for applying energy pulses to the track rails at a selected code rate comprising, a source of energy, respective high and low rate coding contacts, and circuit means for selectively govern-

ing the potential applied to the track rails from said source of energy through said coding contacts in accordance with the code rate selected for transmission.

5. In a coded track circuit for a railway track section, a code transmitter for applying code pulses at selected high and low code rates to the track rails at one end of said track section in accordance with traffic conditions comprising, 10 a source of energy, means including said source of energy for applying code pulses at a relatively high potential to the track rails when said high code rate is selected, means including said source of energy for applying code pulses at a relatively low potential to the track rails when said low code rate is selected, and means responsive to the shunting of the track rails of said track section for selecting said low code rate in preference to said high code rate.
- 20 6. A code transmitter for applying code pulses at selected high or low code rates to the track rails of a track section comprising, a source of energy, respective high and low rate coding contacts, respective high and low resistance track resistors, circuit means for selectively connecting said source of energy across the track rails through said high rate contact and said low resistance track resistor or through said low rate contact and said high resistance track resistor,
- 25 30 an approach control relay, and circuit means for selectively connecting said approach control relay across one or the other of said resistors in accordance with whether said source of energy is connected to the track rails through said high rate contact or said low rate contact.

- 35 7. The combination in a coded track circuit of a source of energy, respective high and low rate coding contacts, respective high and low resistance track resistors, track energization means for selectively connecting said source of energy across the track rails through said high rate contact and said low resistance track resistor or through said low rate contact and said high resistance track resistor, an approach control relay, circuit means for selectively connecting said approach control relay so as to be energized by the voltage drop of one or the other of said resistors selected in accordance with whether said source of energy is connected to the track rails through said high rate contact or said low rate contact, whereby said approach control relay is normally inactive but is rendered active in response to the shunting of the track rails of said track section by a train, said source to be connected to the track rails through said high rate contact as governed by traffic conditions in another track section, only provided that said approach control relay is inactive.

- 40 8. In a code transmitting organization at the exit end of a railway track section, a source of energy, circuit means including limiting resistors and coding contacts for intermittently connecting said source of energy to the track rails of said section at different selected code rates in accordance with traffic conditions in advance, said limiting resistors having different values so that the pulses of each code rate are applied across the track rails at different appropriate potentials, an approach control relay at said exit end of said section governed by the intermittent energization of said track rails and the shunting of said track rails by a train to indicate the conditions of occupancy of said track section, and control means governed by said approach relay for acting on said circuit means
- 45 50 55 60 65 70 75

to select a particular code rate when said section is occupied by a train independent of traffic conditions in advance.

9. In a code transmitting organization at the exit end of a railway track section, a source of energy, high rate coding means including said source of energy and a limiting resistor of a particular value effective when rendered active to apply code pulses of a relatively high potential at said high rate to the track rails of said section, low rate coding means including said source of energy and another limiting resistor of a higher value effective when rendered active to apply code pulses of a relatively low potential at said low rate to the track rails of said section, circuit means controlled in accordance with traffic conditions in the next section in advance for selectively rendering said high or low rate coding means active, and an approach control relay at the exit end of said section governed by the intermittent energization of the track rails and rendered active in response to the presence of a train section for rendering said low rate coding means active and said high rate coding means inactive irrespective of the control provided by said circuit means dependent upon traffic conditions in advance, whereby code pulses of different selected rates and of appropriate potentials for such rates are applied to the track rails to operate the code receiving means at the entrance end of the section in accordance with traffic conditions, and whereby the low rate code pulses of low potential are applied to the track rails while a track section is occupied by a train to thereby save energy from said source and minimize the amount of current to be controlled by the said low rate coding means.

10. In a coded track circuit organization for a section of railway track in which driven code pulses are transmitted from one end of the section to receiving apparatus at the other end that is effective to return inverse code pulses between successive driven code pulses, code apparatus at said one end comprising, a source of energy, a first means including said source of energy for applying code pulses at a relatively high potential to the track rails when said high code rate is selected, a second means including said source of energy for applying code pulses

at a relatively low potential to the track rails when said low code rate is selected, circuit means governed by traffic conditions for the next section in advance for selecting said first or second means dependent upon the then existing traffic condition, and means governed by said inverse code pulses and responsive to the shunting of the rails of said track section for acting on said circuit means to select said low code rate in preference to said high code rate.

11. In a coded track circuit organization for a section of railway track in which driven code pulses are transmitted from one end of the section to receiving apparatus at the other end that is effective to return inverse code pulses between successive driven code pulses, code apparatus at said one end comprising, a source of energy, a first means including said source of energy for applying code pulses at a relatively high potential to the track rails when said high code rate is selected, a second means including said source of energy for applying code pulses at a relatively low potential to the track rails when said low code rate is selected, circuit means governed by traffic conditions for the next section in advance for selecting said first or second means dependent upon the then existing traffic condition, and inverse code receiving means at said one end of said track section responsive to the shunting of the track rails of said track section for acting upon said circuit means to select said second means for applying code pulses at a relatively low potential and at said low code rate irrespective of the traffic condition then existing for the track section in advance.

THOMAS J. JUDGE.
